UNITED STATES PATENT OFFICE

2,329,642

ELECTRICAL APPARATUS

Carl E. Mosley, Overland, Mo., assignor to W. N. Matthews Corporation, St. Louis, Mo., a corporation of Missouri

Application July 17, 1940, Serial No. 345,944

12 Claims. (Cl. 200—115)

This invention relates to electrical apparatus consisting in surge gap and fuse protection elements, and with regard to certain more specific features, to a combined lightning arrestor and fuse.

Among the several objects of the invention may be noted the provision of a surge gap which, under voltage conditions such as encountered during lightning strokes on power lines, will under most conditions effect grounding of surge current but extinguish the accompanying arc in time to prevent grounding of 60-cycle follow-up power current; the provision of a device of the class described which will provide for the expansion of the gases engendered in connection with the values of surge currents to be dealt with, without exploding the apparatus; the provision of a device of the class described which will maintain its rated characteristics for a substantial period and provide a signal when it becomes inoperative after such period; and the provision of combined fuse and surge gap apparatus which is compact in form, simple to operate and economical in cost. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention

Fig. 1 is a side elevation of one form of the invention, a small part being broken away;

Fig. 2 is a vertical section taken on line 2—2 of Fig. 1;

Fig. 3 is a view similar to Fig. 2 showing another form with end parts broken away;

Fig. 4 is a plan view of an insulator carrying the Fig. 4 form of the invention along with a fuse cut-out;

Fig. 5 is a front elevation of the Fig. 4 device;

Fig. 6 is a fragmentary view similar to Fig. 2, but on a plane at right angles and showing a signal attachment; and,

Fig. 7 is a section taken on line 7—7 of Fig. 5.

Similar reference characters indicate corresponding parts throughout the several views of the drawings.

Referring now more particularly to Figs. 1 and 2, there is shown at numeral 1 an insulating tube composed, for example, of wrapped "Bakelite,"

to the upper end of which is attached (by means of an anchor pin 3) an enclosing, conducting head 5. This head includes a lug 7 which has an opening for the reception of an electrode 9 held by set screws 11. The electrode 9 forms the point of entry into the present apparatus of the current which is to be sent to ground. In the present example this electrode is in spaced relation to an inlet electrode on a transformer bushing (not shown) which is in conducting relation to the transformer supply line parts, which are subjected to lightning strokes and the like. Thus the electrode 9 forms one side of a gap which brings current to the present apparatus.

In order that the device may be made in one length for various applications, the electrode 9 is bent into an S-shape, as shown, for rotation as well as sliding in 7. Hence the end 10 may be adjusted to various situations.

At the other end of the tube 1 is threaded a removable conducting head or cap 13 held in fixed position by means of a set screw 15. This head is in the form of an open ended cup (see opening 16), from which extend spacing pillars 17, the latter forming openings 18. The central pillar in Fig. 1 is shown broken away for more clearly showing parts behind it.

At their lower ends, the pillars join with an integral disc or floor part 19 from which extends a threaded portion 21 for receiving a holding nut 23 and lock washer 25. Thus the device may be supported upon an S-shaped grounding bracket, such as the one shown at 27. The bracket is held between the disc 19 and nut 23 for conducting engagement and carried on a transformer case 12. The case 12 is grounded. Holding stud 14 permits rotary horizontal adjustment where necessary, in addition to the rotary vertical adjustment and horizontal translation afforded by the S-shaped electrode 9 and its screws 11.

Adjustably threaded within the extension 21 is an electrode 29. A screw-driver slot 31 provides for adjustment and a lock nut 33 is adapted to preserve a given adjustment.

Riveted to the cap 5, as at 35, is a long electrode 37. This extends in spaced relation to a cylindric horn fibre liner 39 within the tube 1. The purpose of making the electrode 37 long, and also tube 1, is to obtain ample dielectric strength between members 5 and 13.

Within the lower end of the liner 39 is a horn fibre plug 41 which includes a counterbore 43 at its top for receiving snugly the lower end of the electrode 37. Through the plug 41 is a relatively small opening 45 which is of the order of .040"

in diameter. This opening extends through the plug 41 from its counterbore 43 to its lower flat surface 47. The plug 41 plugs the cylinder 1, 39.

The upper end of the lower electrode 29 is flat with the exception of a semi-cylindric channel 49 which is formed across it for the purpose of forming a communication between the small bore 45 and the atmosphere, via openings 18.

The small bore 45 forms a gap between the electrodes 37 and 29 which must be broken down by the voltage between the rod 9 and the ground member 27 before an arc can be established. The diameter of the hole 45 is such that under the conditions to which the apparatus is applied, the voltage due to a lightning stroke or the like breaks through the gap constituted by the passage 45, permitting any surge currents, due to the abnormal voltage, to flow to ground. This is by way of conducting members 9, 5, 37, gap 45, opening 49, electrode 29, and then to the ground member 27 and case 12. The arc due to the surge current in the passage 45 is promptly snuffed by the gas engendered by the gas-evolving horn fibre of the plug 41. This gas deionizes the arc quickly, so that it does not constitute a good conductor for the 60-cycle, follow-up power current at normal voltage. Other materials may also be used for the snuffing purpose. Thus the follow-up current does not continue the arc under normal conditions, and an ungrounded condition is quickly reestablished after the abnormal voltage conditions have passed.

The purpose of the counterbore 43 is to increase the impedance between the lower end of the long electrode 37 and the upper end of the short electrode 29 outside of the plug 41 to a value which is greater than the impedance through the opening 45. This forces the arc to be established within the opening 45 wherein it is quickly broken.

I have found that the larger the opening 45, the more power, follow-up current is liable to pass through the device after a surge current has started an arc. On the other hand, the surge current protection is reduced with smaller holes. I have found that the .040" dimension for the diameter of a gap one inch long at 45 is a satisfactory value for most ordinary 60-cycle power lines.

Among the advantages of the invention is its simplicity, the construction being quite compact and easily mounted.

Should the hole 45 erode out, due to repeated discharges, the cap 13 may be unscrewed after loosening the set screw 15 and a new plug 41 inserted.

It will be understood that at the instant the arc forms in the passage 45, due to the surge current, gases are formed which are expansive. Expansion is accommodated to atmosphere through the semi-cylindric opening 47. This under most lightning stroke conditions prevents the plug 41 from exploding.

Some times, after the opening 45 has eroded out after repeated satisfactory operation, upon the next discharge the arc is no longer extinguished. Then the 60-cycle normal-voltage follow-up current will pass through the apparatus to ground and the circuit breaker on the line will then open. It is this opening that the present device ordinarily prevents. When the circuit breaker does open, it is desirable to know which one of a number of the present devices caused such a result. For this purpose, the signal device

of Fig. 6 may be used which consists of a coil spring 51 attached by means of a screw 53 to the lower conducting head 13 and sprung into the position shown in solid lines. In this position its opposite straight end 55 is soldered to the lower electrode at 51. That is at a point just below the opening 49. Any undesirable 60-cycle follow-up current, in passing from the electrode 37 to the electrode 29, generates heat which melts the solder 51. The spring 51 then springs straight out to the dotted-line position shown in Fig. 6. This is a signal to an inspecting lineman that the particular unit requires a new plug 41. It will be understood that the solder is melted only by the heat of the 60-cycle follow-up current, and that the surge current accompanying the ordinary lightning stroke which is successfully snuffed out does not melt the solder 51. Hence, as is desired, under the latter circumstances no signal will be given by the spring 51.

In Fig. 3 is shown another form of the invention in which like numerals designate like parts. In this construction, however, there is substituted for the lower conducting element 13 of Fig. 2 a different shape of conducting element 59 which has a floor 61 which, in view of the threading action of 59 on the tube 1, engages the lower end of the plug 41 to force the plug into engagement with the lower end of the inner electrode 31. This floor 61 also forms an electrode. Below this floor are pillars 17 and openings 18. Below the pillars and openings is an enclosure 63 having a cylindric extension 65 for reception of a braided flexible conductor 67, the latter being soldered or otherwise fastened.

The upper conducting cap 5 of Fig. 2 is also changed, being provided with an extension 71 used for receiving the soldered end of an upper flexible conductor 73.

The mounting of the Fig. 3 variation is shown in Figs. 4 and 5. In these figures numeral 15 indicates an insulator carried upright on a more or less central bracket 77. At the upper end of the insulator is a conducting terminal member 79 having a connection 81 for a line wire (not shown). The terminal 79 has adjustably arranged thereon (as indicated at 82) one element 83 of a horn gap 85. The other element 87 of the gap is adjustably carried at 89 on a fixed conducting extension 91 clamped to the insulator at 93. The extension 91 is provided with a V-shaped entry 95 ending in a spherical socket portion 97. The latter engages a spherical contact ferrule 99, to which is attached the upper flexible conductor 73. A large rigid ring 101 is formed at the upper end of the ferrule 99.

The lower flexible conductor 67 like wise fastens to a similar spherical shaped contact ferrule 99, but this carries a small ring 103. The lower ferrule 99 is for cooperation with a spherical socket 105 in the hooked end 107 of a rotary, biased arm 109. The hooked character of the arm 109 is shown in Fig. 7.

The arm 109 is pivoted at 111 and is in conducting relation with respect to the bracket 77. A spring 113 normally biases the arm downwardly. The bracket 77 is grounded, by a wire connected at 78.

The upper terminal 79 carries a second rigid arm 115 having a guiding entry portion 117 for the upper conducting ferrule 99 of a fuse link, the latter being indicated generally at 119. A spherical socket is provided for the spherical fer-

rule 99, and above is carried another large ring 101.

At the lower end of the fuse link is another spherical conducting ferrule 99 below which is another small ring 103. The ferrule 99 is also cradled in a hook 127 which is on the end of a rotary arm 129 pivoted at 131 on a terminal 135 having a line wire connection 137. A spring 139 normally biases the lever 129 downward.

The fuse link 119 comprises an insulating tube 121 which surrounds a fusible portion (not shown) between an upper flexible conductor 123 and a lower flexible conductor 125. The details within the tube 121 form no part of the present invention, and if desired may be such as shown in Mosley et al. Patent 2,067,577, dated January 12, 1937.

The above-described mounting construction provides a simple method for mounting in tension both a fuse link and a lightning arrestor from a single insulator. The arrangement of the large ring 101 at the top of the fuse and of the lightning arrestor assures that neither will be mounted upside down. This is because the ring 101 is made large enough to go over the ball end of a lineman's stick. The rings 103 are not large enough to do this.

The lineman mounts the ring 101 of either device on his hook stick and raises it. He then dangles the lower flexible conducting element (125 or 67 as the case may be) and directs it in from the rear into its respective lower hook. He then pushes upward which rotates upwardly the normally downwardly-biased lever (129 or 109 as the case may be). He then guides the upper ferrule 99 into position over the upper rigid arms 115 or 91, as the case may be. After disengagement of the stick, the downward bias of the arms 129 and 109 results in a tendency to seat the spherical ferrules 99 in their respective spherical seats and to hold the respective devices in place.

It is to be understood that when the fuse link 119 blows, it permits separation of the conductors 123 and 125 and that the lower arm 129 therefore springs downward.

The lightning arrestor feature shown at the right of Fig. 5, when it operates does not have any separating effect between the upper flexible conducting element 73 and the lower one 67. The tension in the lower arm 109 in this case is only for maintaining a properly tensioned, mounted condition.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. Surge gap apparatus comprising an elongate insulating tube, a first conductor attached exteriorly to one end of the tube and enclosing the same, an electrode extending from said conductor lengthwise of the interior of said tube, a second conductor attached to the other end of the tube and having an opening communicating with the atmosphere, an electrode carried by said second conductor, and an insulating plug between said electrodes, said plug having a relatively small opening therethrough connecting said electrodes, said second-named electrode having an opening connecting said opening in the plug with

atmosphere through the opening in the second conductor, said last-named electrode being adjustable against the plug to push said plug against said interior electrode.

5. Surge gap apparatus comprising spaced electrodes, insulating means between electrodes having an opening therethrough permitting passage of surge currents under conditions of surge voltage but normally resisting power currents under power voltage, signal means comprising a deflected and tensioned spring anchored at one end and having its opposite end attached to one of the electrodes adjacent said opening by material adapted to resist melting by the surge current but adapted to melt in response to power current flowing abnormally at power voltage so that the spring moves to a new position.

2. Surge gap apparatus comprising spaced electrodes, insulating means between electrodes having an opening therethrough permitting passage of surge currents under conditions of surge voltage but resisting power currents at power voltage, and signal means responsive to current flowing abnormally at normal voltage, to provide a 20 signal.

3. Surge gap apparatus comprising spaced electrodes, insulating means between electrodes having an opening therethrough permitting passage of surge currents under conditions of surge voltage but resisting power currents at power voltage, and signal means responsive to current flowing abnormally at normal voltage, to provide a 25 signal.

4. Surge gap apparatus comprising an insulator, a line terminal thereon carrying one side of an arc gap, a rigid arm carrying the other side of said arc gap and providing an attachment, 30 a third arm pivoted thereon and biased away from the rigid arm, said biased arm having a holding attachment thereon, an insulating tube, a surge gap in the tube, and conducting means on opposite sides of the gap and having 35 connecting means for attachment respectively to said arms.

5. Surge gap apparatus comprising an insulator, a line terminal thereon carrying one side of a fixed arc gap, a rigid arm carrying the other side of said arc gap and providing an attachment, 40 a third arm pivoted thereon and biased away from the rigid arm, said biased arm having a holding attachment thereon, a removable insulating tube, a surge gap in the removable tube, conducting means on opposite sides of the gap and having connecting means for removable attachment respectively to said arms, a second pivoted arm on the insulator biased away from 45 said line terminal, a second rigid arm extending from said line terminal, and a removable fuse link adapted to be tensioned between said second rigid arm and said second biased arm.

6. Electrical protective apparatus comprising a grounded support, an insulator carried on said 55 support, line terminals on opposite ends of the insulator, one of which provides one side of an arc gap, a tensioned fuse link removably supported between said line terminals, means spaced from said line terminals and extending from said 60 insulator and providing another side of said arc gap, means extending from the grounded support, and a tensioned gap member removably supported between said last-named extending means.

7. A lightning arrestor comprising an elongated hollow insulating tube, a first conductor closing one end of said tube, a second conductor attached to the other end of the tube and having lateral outlets, a first electrode extending from the first conductor into the tube, a plug filling the tube adjacent the inner end of said first electrode, said plug having a small opening extending through the plug, and a second electrode 70 adjustably fastened to said second conductor and being longitudinally movable to clamp said plug

against the first electrode, and a lateral opening in said holding member communicating between said opening in the plug and said lateral openings.

8. A lightning arrestor comprising an elongated hollow insulating tube, a first conductor closing one end of said tube, a conductor attached to the other end of the tube and having lateral outlets, a first elongate electrode extending from the first conductor into the tube and spaced from the walls of the tube, an elongated plug filling the tube adjacent the inner end of said first electrode, said plug having a single small but long opening extending through it, and a second electrode adjustably fastened to 15 said second conductor and adjustable in position to clamp said plug against the first electrode, and a lateral opening in said second electrode communicating between said opening and said lateral openings.

9. A lightning arrestor comprising an elongated hollow insulating tube, a relatively short conducting cap covering one end of said tube, a second short conductor attached to the other end of the tube and having lateral outlets, a first electrode extending from the cap into the tube and spaced from the walls of the tube, a plug filling the tube adjacent the inner end of said first electrode, said plug having a single small opening extending through it, and a second electrode adjustably fastened to 20 said second conductor and adjustable in position to clamp said plug against the first electrode, and a lateral opening in said second electrode communicating between said opening in the plug and said lateral openings.

10. Surge gap apparatus comprising an insu-

lating cylinder, a conductor enclosing the upper end of the cylinder, an open conductor at the lower end of the cylinder, flexible conductors extending from said conductors for mounting electrodes extending from said conductors, a plug within the tube and engaged by said electrodes, said plug having an opening therethrough, and being held between said electrodes, and lateral openings communicating with said opening in the plug.

11. Surge gap apparatus comprising a tubular insulator, an enclosing conductor on one end of the insulator, a laterally open conductor on the other end, an electrode extending from said enclosing conductor within the tube, said open conductor having a threaded extension for attachment purposes, a second electrode threaded through said extension, a plug in said insulating tube and located between said electrodes and having a relatively small opening therethrough, said electrode in the open conductor being adjustable by its threads to clamp the plug between said electrodes.

12. Surge gap apparatus comprising an insulator, a line terminal thereon carrying an extension providing one side of an arc gap, a rigid arm on the insulator which is spaced from the line terminal and carries the other side of said arc gap and providing an attachment, a third arm pivoted on the insulator biased away from the rigid arm, said biased arm also providing an attachment, an insulating tube having a surge gap therein, and conducting means on opposite sides of the tube for attachment between said rigid arm and said third arm.

CARL E. MOSLEY.
